MANIPULATOR

Maurice P. Sieger, Mount Lebanon, Pa., assignor to United Engineering and Foundry Company, Pittsburgh, Pa., a corporation of Pennsylvania

Application September 10, 1953, Serial No. 379,334

9 Claims. (Cl. 80—48)

This invention relates to an improvement in apparatus for use in handling ingots and the like and in particular to an improvement in manipulators adapted to engage with, turn and position heavy ingots rapidly and efficiently between rolling mill passes.

In a given rolling mill set up, not only is the speed of the mill a factor in determining the rolling capacity but the ability of the auxiliary apparatus to function efficiently and quickly in the manipulation of the workpiece must also be considered inasmuch as such operations usually require as great as 60% of the total time required for actually rolling the workpiece. As the ingots to be rolled may weigh 60,000 pounds or more, they are difficult and cumbersome to maneuver and the loss of time incident to turning and positioning such ingots is of such consequence that the need for improved handling and manipulating apparatus becomes readily apparent.

It is one of the objects of this invention, therefore, to provide apparatus for efficiently and quickly manipulating heavy ingots between the passes of a rolling mill.

It is another object of this invention to provide a manipulator having lifting finger operating means associated therewith which are rugged and substantial and not subject to the mechanical limitations of manipulators of the type presently employed in industry.

Still another object of this invention is to provide a manipulator having lifting fingers which are so arranged that they may be readily placed into contact with a workpiece for carrying out a manipulating operation and yet which can not become damaged even though in the lowering operation the fingers may strike an ingot and be interrupted in their downward travel.

These objects, as well as the various other features and advantages of this invention, will become apparent from a reading of the following specification and accompanying drawings of which:

Figure 1 is a plan view of apparatus embodying features of the invention herein disclosed;

Figure 2 is a sectional view taken at II—II of Figure 1, and

Figure 3 is a sectional view taken at III—III of Figure 1.

With reference to Figure 1, there is shown therein a horizontal rolling mill 11 and a vertical mill 12 adjacent thereto through which articles such as ingots and the like are passed and reduced to the cross sections desired. Adjacent to the entry side of the vertical mill 12 there is shown a feed table 13, having driven rolls, which receives an ingot from and directs it into the mill. In conjunction with the feed table there is provided a manipulator assembly 14 adapted to engage with and position an ingot transversely on the table between the passes through the mills.

2

The manipulator comprises, in opposed relation, two side guides 15 and 16 which are located above the table 13, being movable toward and away from one another transversely thereof. The guide 15 is provided with a plain guide face 15a whereas the side guide 16 has four vertical slots 17 formed in the face 16a thereof, in each of which there is received for vertical sliding movement a lifting finger 18. Each of the fingers has at its lower end a stepped ledge 19 extending in a transverse direction with respect to the feed table rolls and, in their lowermost positions, slightly below the surface of the table. Three of the lifting fingers 18 are pivotally secured to levers 21 and the fourth to a lever 21a all of which are contained in planes located at right angles to the plane of the face 16a of the side guide 16, the levers 21 and 21a being keyed to a shaft 22 mounted in suitable bearings 23 provided on the frame 24, which frame is rigidly secured to the ends of the upper rams 25 of the manipulator. A link 26 is secured to the inner end of the lever 21a and to a second lever 27 pivotally mounted upon a shaft 28 supported in suitable bearings mounted upon the frame 24. The opposite end of the lever 27 is provided with a cam follower 29 which makes contact with the upper flat cam surface 30 formed on a vertically and longitudinally movable table 31. Each of the rams 25 is slidably supported at its forward end on a suitable bearing 32 having a pivotal connection with a supporting shaft 32a and having secured to one end thereof the side guide 16. The shaft 32a, in turn, is supported in suitable bearings upon a pedestal 33 mounted upon a frame 34. As shown in Figure 2 the lower frame 34 also supports the pedestal bearings 35 within which the ends of the feed table roll 36 are rotatably secured. Although not shown in the drawings, adjacent to the outer ends of each of the upper rams 25 bearings similar to those at 32 are also provided so that the rams and their associated parts are adequately supported for level transverse movement across the feed table 13. Movement of the rams 25 and the side guide 16 is accomplished by means of a reversing motor 37 connected to a gear reduction drive unit 38, the shaft 39 of which is coupled to a line shaft 41 upon which there are secured pinions 42 in meshing relationship with racks 43 formed on the lower surface of the rams 25. For the side guides 15 there are provided rams 40 having rack and pinion driving connections and a line shaft 44 connected to a gear reduction unit 45 and reversing driving motor 46. As noted heretofore, the table 31 is moved simultaneously in both a vertical and a longitudinal direction. Since the cam surface 30 remains level at all elevations, movement of the rams toward and from the feed table and carrying with them the lifting fingers and cam follower associated therewith will not disturb the relative vertical positions of the lifting fingers.

With reference to Figures 2 and 3, vertical and longitudinal movement of the table 31 is accomplished by means of a crank shaft 47 on which there are formed double cranks 48 and 49. For driving the crank shaft 47, a worm wheel 51 is secured thereto which is engaged with a worm 52 keyed to a drive shaft 53 connected to a suitable motor, not shown. The crank 48 is connected directly to the vertically movable table 31 so that as the crank is rotated in the counterclockwise direction, as shown in Figure 2, the table portion connected thereto will rise and at the same time the entire table will be displaced in a longitudinal direction toward the right. In order to assure uniform vertical displacement of the table

so that it will be maintained level in all of its vertical positions, a system of links is provided. A link 54 is pivotally connected to the crank 49 and to a lever 55 of a bell crank 56 which is keyed to a shaft 57 mounted in suitable bearings upon a frame 58. The other lever 59 of the bell crank has pivotally connected to its end a vertically disposed link 61 which, in turn, is pivotally connected to the table 31. As the double cranks 48 and 49 are rotated, both ends of the table 31 will rise the same distance and, at the same time, the table will be permitted to move in a longitudinal direction to the extreme positions indicated by the dot and dash lines in Figure 2. Above the double crank, there is provided a cover 60 for preventing scale and other foreign matter from dropping down into the bearings and mechanism thereof.

Operation of the apparatus comprising this invention may be briefly summarized as follows:

An ingot is placed upon the mill feed table and is run up to and stopped at a position intermediate the two side guides 15 and 16. By actuation of the two sets of rams 25 and 40 the side guides are then brought up to a position adjacent the sides of the ingot thereby to orient the ingot in an axial longitudinal direction, the fingers 18 of the side guide 16 being in their lowermost positions. If the ingot is to be turned about its longitudinal axis, the guide 15 is backed away a sufficient distance so as to provide adequate clearance for carrying out the turning operation and the double cranks 48 and 49 are rotated whereby the table 31 rises thereby causing the fingers to rise and the stepped ledges 19 thereof to engage the under side of the ingot, thus to turn it to its new position. The ingot is aligned with the mill merely by pushing it by one of the side guides to the desired transverse position on the table. In the event it should be required that the ingot be turned about its axis 180°, the foregoing operation is repeated. Should the fingers in being lowered inadvertently strike the edge of an ingot so as to interfere with the downward travel thereof, the apparatus will not be damaged since the cam follower 29 merely will lose contact with the table cam surface 30 and remain suspended in the air until such time as the ingot is moved to permit the fingers to drop and the cam and follower again to make contact with one another.

In accordance with the provisions of the patent statutes, I have explained the principle and operation of my invention and have illustrated and described what I consider to represent the best embodiment thereof. However, I desire to have it understood that within the scope of the appended claims, the invention may be practiced otherwise than as specifically illustrated and described.

I claim:

1. Ingot manipulating apparatus for use in combination with a rolling mill feed table comprising a pair of oppositely disposed guides movable transversely of said table and toward and away from one another, a plurality of vertically extending longitudinally disposed ingot engaging fingers in slidable engagement with one of said guides, a cam, a cam follower, said cam and cam follower being separable from one another and operably connected to said fingers, and means for imparting vertical motion to said cam and cam follower thereby to impart vertical motion to said fingers.

2. Ingot manipulating apparatus for use in combination with a rolling mill feed table comprising a pair of oppositely disposed guides movable transversely of said table and toward and away from one another, a plurality of vertically extending longitudinally disposed ingot engaging fingers in slidable engagement with one of said guides, a cam follower operably connected to said fingers, a cam, said follower adapted to be engaged with and disengaged from said cam and means operably connected to said cam for imparting vertical motion thereto thereby to impart vertical motion to said cam follower and to said fingers.

3. Ingot manipulating apparatus for use in combination with a rolling mill feed table comprising a pair of oppositely disposed guides movable transversely of said table and toward and away from one another, a plurality of vertically extending longitudinally disposed fingers in slidable engagement with one of said guides, an ingot engaging ledge portion at the lower end of each finger, normally below the surface of said table, and extending outward therefrom in a direction toward the other of said guides, a cam follower operably connected to said fingers, a cam, said follower adapted to be engaged with and disengaged from said cam and means operably connected to said cam for imparting vertical motion thereto thereby to impart vertical motion to said cam follower and to said fingers.

4. Ingot manipulating apparatus for use in combination with a rolling mill feed table comprising a pair of oppositely disposed guides movable transversely of said table and toward and away from one another, a plurality of vertically extending longitudinally disposed fingers in slidable engagement with one of said guides, an ingot engaging ledge portion at the lower end of each finger, normally below the surface of said table, and extending outward therefrom in a direction toward the other of said guides, a cam follower, a lever interconnecting said fingers and said follower, a cam, said follower adapted to be engaged with and disengaged from said cam, and a crank mechanism connected to and for imparting vertical motion to said cam thereby to impart vertical motion to said cam follower and to said fingers.

5. Ingot manipulating apparatus for use in combination with a rolling mill feed table comprising a pair of oppositely disposed guides movable transversely of said table and toward and away from one another, a plurality of vertically extending longitudinally disposed fingers in slidable engagement with one of said guides, an ingot engaging ledge portion at the lower end of each finger, normally below the surface of said table, and extending outward therefrom in a direction toward the other of said guides, a shaft, a plurality of levers secured to said shaft and pivotally secured to said fingers, a cam follower operably connected to one of said levers, a cam, said follower adapted to be engaged with and disengaged from said cam and means operably connected to said cam for imparting vertical motion thereto thereby to impart vertical motion to said cam follower and to said fingers.

6. Ingot manipulating apparatus for use in combination with a rolling mill feed table comprising a pair of oppositely disposed guides above said table, rams secured to said guides for moving them in a direction transversely of said table and toward and away from one another, a plurality of vertically extending longitudinally disposed fingers in slidable engagement with one of said guides, an ingot engaging ledge portion at the lower end of each finger, normally below the surface of said table, and extending outwardly therefrom in a direction toward the other of said guides, a rocker shaft, a pair of interconnected levers one of which is secured to said shaft and the other provided with a roller at one end thereof, a plurality of levers secured to said shaft and pivotally secured to each of said fingers, a table along which said roller travels on actuation of said rams, and means for raising said table vertically and for maintaining level the surface thereof thereby to impart vertical motion to said fingers.

7. Means for actuating an ingot tilting finger in a substantially vertical direction comprising a lever pivotally attached to the finger, a separable cam and cam follower operatively engaged with said lever, and means for actuating said cam and cam follower thereby to impart vertical motion to said finger.

8. Means for actuating an ingot tilting finger in a substantially vertical direction comprising a lever operatively secured to said finger, a horizontally disposed flat cam and a cam follower adapted to be engaged with and dis-

engaged from one another and operatively engaged with said lever, and a double crank mechanism in engagement with and for imparting vertical motion to said cam while maintaining the cam surface thereof in parallel planes throughout such motion.

9. Means for actuating an ingot tilting finger in a substantially vertical direction comprising a lever operatively secured to said finger, a cam, a cam follower adapted to be engaged with and disengaged from said cam and secured to said lever and means comprising a mechanism having double cranks offset at right angles with respect to one another and so connected to said cam as to im-

part vertical motion thereto without disturbing the horizontal attitude of the surface thereof.
